FLY SWATTER

Abraham Sorkind, Brawley, Calif.

Application February 18, 1944, Serial No. 522,940

5 Claims. (Cl. 43—137)

The invention relates to a fly swatter, and more especially to structural refinements over the subject matter of letters Patent No. 2,312,780, issued on or about the 2nd day of March, 1943.

The primary object of the invention is the provision of an article of this character, wherein the swatting blade or section thereof is readily and easily removed, it being detachably clamped in place for association with the handle shank or stem of the article, the clamping medium for the blade or section being swingingly supported to close against the said section or blade and in this position is fastened securely to the said shank or stem, thus holding such blade or section from becoming accidentally detached, yet when it becomes unfit for service the same can be removed or detached and a new blade or section substituted, thereby avoiding the discarding of the article as a whole.

Another object of the invention is the provision of an article of this character, wherein the construction of the clamping medium materially strengthens the joining area of the handle shank or stem with the blade or section, in that the latter is partially folded about such area and reinforced by said medium, the latter being hingedly supported for opening and closing movements, whereby the blade or section can be readily detached without requiring special tools or a tool or skilled workmanship, there being no permanent tacking, wire stitching or other similar fasteners required for this purpose.

A further object of the invention is the provision of an article of this character, wherein material refinements are involved therein over the subject-matter of Letters Patent No. 2,312,780, issued on or about March 2, 1943.

A still further object of the invention is the provision of an article of this character, which is extremely simple in construction, thoroughly reliable and efficient in its purpose, strong, durable, susceptible of withstanding severe usage, readily and easily handled, it being possessed of a minimum number of parts, and inexpensive to manufacture.

With these and other objects in view the invention consists in the features of construction, combination and arrangement of parts as will be hereinafter more fully described in detail, illustrated in the accompanying drawing, which shows the preferred embodiment of the invention, and pointed out in the claims hereunto appended.

In the accompanying drawing:

Figure 1 is an elevation of the article constructed in accordance with the invention.

Figure 2 is a fragmentary opposite face view thereof.

Figure 3 is a sectional view taken on the line 3—3 of Figure 1 looking in the direction of the arrows.

Figure 4 is a fragmentary perspective view with the clamping medium in an open position for the removal of the swatting blade or section.

Figure 5 is a sectional view taken on the line 5—5 of Figure 1 looking in the direction of the arrows.

Similar reference characters indicate corresponding parts throughout the several views in the drawing.

Referring to the drawing in detail A designates generally the fly swatter or article in its entirety constructed in accordance with the invention, which comprises a straight shank or stem 10 formed with double wire lengths having a slightly spread open-loop handle end 11 and a substantially triangular shaped opposed head end 12, the shank or stem and these ends being created from a single piece of wire. The double lengths of wire at a determined point along the stretches at the shank or stem may be intercoiled or twisted together as at 13, to avoid the separation of the lengths of wire, which might result in the spreading thereof and similarly the head and handle ends, respectively.

The outer straight cross run portion 14, at the head end 12 forms a pintle for a hinged sleeve 15 cut and bent from a clamping medium 16 in the form of a plate, which for a major portion thereof is correspondingly shaped to the head end 12, and in this manner the said medium can be swung away from the said head end or to an open position thereto or swung against the said head end to closed position, resultant from the hinge connection of the plate and head end.

Adapted to be detachably clamped to the head end 12 is a swatting blade or section 17, in this instance, made from wire mesh fabric, although it may be made from any other suitable material to meet the requirements intended thereof. This blade or section 17 is of a flat sheet-like form and inherently has a slight flexing quality, it normally being of substantially rectangular shape. The clamping plate 16 detachably secures the blade or section 17 onto the head end 12.

It is preferable to have the opposite side edges of the plate 16 which are angled correspondingly to the side stretches 18 of the head end 12, folded on themselves to effect reinforced blunt edgings, and curled as at 19 for seating when this plate

16 is in clamping position with relation to the head end 12.

The plate 16 is formed with a half-sleeve formation 20 matching the shank or stem 10 for its seating therein when the said plate is in clamping position. This formation 20 when seating the shank or stem 10 with the blade or section 17 in attached position on the head end 12 is embraced by a coiled wrapping of wire 21, which is also carried about the said shank or section 10 at the open side of the formation 20, and in this manner the plate 16 is securely held in clamping position.

The blade or section 17 is removably attached to the head end 12 by placing one end portion of such blade or section over the latter at that side opposite to the plate 16, which at this time is in open position relative to this head end 12, then uniformly folding the corners 22 of this blade or section 17 over and against the said end 12. When the corners 22 have been so folded the plate 16 will be closed against the same, and the formation 20 fastened to the shank or stem 10 in the manner before explained, and thus the said shank and blade are firmly and securely connected together, and the article completed for service.

When the blade or section 17 becomes unfit for service then the clamping plate 16 is opened so that a new blade or section can be substituted for detachable connection to the shank or stem 10, and in this way increase the usefulness of the handle.

What is claimed is:

1. An article of the kind described, comprising an operating handle shank having a head at one end provided with a cross pintle, a swatting blade having an end portion overlapping said head, opposite corners of said end portion folded about the sides of the head to lie against the face thereof opposite to that occupied by the said end portion of the blade, a clamping medium hinged

to the pintle and overlying the folded corners of the blade for detachably securing the latter to the head and means detachably securing the clamping medium to said handle shank.

5 2. An article of the kind described, comprising an operating handle shank having a head provided with a pintle transversely thereof, a swatting blade having an end portion overlapping said head, and folded about the same, and a clamping plate hinged to the pintle and overlying the folds of said end portion for detachably securing the blade to the head and means detachably securing the clamping medium to said handle shank.

15 3. An article of the kind described, comprising an operating handle shank having a head, a swatting blade having one end portion overlapping the head, a clamping plate hinged to the head for detachably securing the overlapping end portion of the blade to the head, and means detachably fastening the clamping plate to the handle shank.

20 4. A fly swatter comprising a handle having a head at one end consisting of side arms and a cross arm, a swatting blade having one end overlapping the head with its corners folded over the side arms of the head, a clamping plate hinged to the cross arm of the head having its side edges bent down to seat against the side arms of the head, and means detachably securing said plate in clamping position.

25 5. A fly swatter comprising a handle having a head at one end consisting of side arms and a cross arm, a swatting blade having one end overlapping the head with its corners folded over the side arms of the head, a clamping plate hinged to the cross arm of the head for detachably securing the folded corner portions of the blade to the head, and means detachably securing the free end of said plate to said handle.

ABRAHAM SORKIND.
